NETHERLANDS.

CARTRIDGE-BELT FOR MACHINE-GUNS.

1,136,956.

Specification of Letters Patent. Patented Apr. 27, 1915.

Application filed August 9, 1912. Serial No. 714,232.

To all whom it may concern:

Be it known that we, JACOBUS HENNEVELD and ALEXANDER LEMEI, subjects of the Queen of the Netherlands, respectively residing at 5 3 Nieuwe Heerengracht, Laandam, and 14 Gijsbrecht van Aemstelstraat, Amsterdam, Netherlands, have invented certain new and useful Improvements in Improved Cartridge-Belts for Machine-Guns, of which 10 the following is a specification.

This invention relates to cartridge belts for machine guns, of the type comprising two bands sewn together by transverse stitches.

15 The present invention has for object an improved cartridge belt having the advantage that the cartridges are so held that they cannot fall out of the belt or be pressed out owing to shrinking of the belt, should the 20 latter become damp.

The improved belt is also more flexible, lighter and cheaper to make than the belts hitherto used.

25 The invention consists in an improved cartridge belt for machine guns in which two bands of equal breadth are connected together by short transverse seams at each longitudinal edge only, in such a manner that at one edge of the belt the cartridge 30 cases, and at the other the projectiles, are gripped between transverse seams, while the central part of the cartridges, and particularly the conical part of the casing thereof, are not held in any way by the bands.

35 When sewing the stitches, care has to be taken that the cartridges will be held at the correct distance apart required by the machine gun with which the belts are to be used.

40 One example of the improved cartridge belt is illustrated in the accompanying drawings, in which,

Figure 1 is an elevation of the belt partly filled with cartridges, Fig. 2 a top plan, and 45 Fig. 3 a bottom plan.

The bands 1 and 2 of durable material are sewn together at both longitudinal edges by means of short transverse seams 3 preferably machine stitched. The middle parts of the 50 two bands between the lines I-II and III-IV thus simply lie on each other without being connected in any way. The seams on the upper edge of the belt are spaced at

such a distance that the casing 4 of the cartridges to be placed in the belt can be inserted between the two bands so as to be firmly held there, while the thinner projectile 5 is similarly held between the two bands at the lower edge of the belt, where the seams are closer together, for the purpose of enabling the said projectiles to be gripped. The seams at the edges of the bands are so arranged that the cartridges when inserted in the belt are at the desired distance apart.

It is obvious that in the improved strap the cartridges are gripped by both edges of the belt only over a length corresponding to that of the seam 3. The central part of the cartridges and particularly the conical part 6 of the casing, lie quite freely between the bands 1 and 2. Should the band shrink, owing to becoming damp, the cartridges will, it is true, be more tightly held in the belt, but the conical part of the cartridge 75 will never be firmly held, so that the cartridge will retain its position in the belt under all conditions. If the conical part of the smooth cartridge were firmly held as in known cartridge belts for machine guns, 80 which have a connecting seam extending across the whole breadth of the band, the cartridges would be partly pushed out of the belt by the resulting forces. These cartridges, when the belt was in use, were apt 85 to drop out owing to the vibration of the machine gun, and in any case the cartridges were not all inserted by equal amounts in the strap; which caused irregularities in the firing. All these drawbacks are obviated by 90 the improved belt.

The belt hereinbefore described is perfectly flexible, so that when filled it can be folded quite flat and placed in a box or case. The cartridges cannot slip out of the belt 95 during transport, and the latter takes up so much less room that, whereas with known belts 250 cartridges inserted in the belt could be placed in one box, with the improved belt this number can be raised to about 300. 100

The improved strap moreover can be made very quickly and cheaply, and the whole ammunition supply for machine guns kept stored in the belts and transported therewith. The time absorbed by inserting the 105 cartridges in the belt in the field is thus

saved. In addition the improved belt is much lighter than the known belts in which the transverse seams are replaced by riveted brass strips, the former weighing only about 5 10 ozs. and the latter $2\frac{1}{2}$ lbs.

What we claim is:

1. An improved cartridge belt for machine guns, comprising two bands held together by coöperating pairs of transverse seams extending a short distance from each 10 side of the respective longitudinal edges of the bands, the seams of each pair at one edge of the bands being closer together than the seams of the pair of the other edge.
- 15 2. An improved cartridge belt for machine guns, comprising two bands held together by coöperating pairs of transverse seams extending a short distance from each side of the respective longitudinal edges of 20 the bands, the intramarginal portions of the bands being continuous and free of seams.
- 25 3. An improved cartridge belt for machine guns, comprising two bands held together by coöperating pairs of transverse seams extending a short distance from each side of the respective longitudinal edges of the bands, the part of the bands adjacent to

the conical part of the cartridge being continuous and free from transverse seams.

4. An improved cartridge belt for machine guns, comprising two identical bands held together by coöperating pairs of transverse lines of stitches extending a short distance from each side of the respective longitudinal edges of the bands, the intramarginal portions of the bands being free of 30 35 seams.

5. An improved cartridge belt for machine guns, comprising two identical bands held together by coöperating pairs of transverse lines of stitches extending a short distance from each side of the respective longitudinal edges of the bands, the part of the bands adjacent to the conical part of the cartridge being free from transverse seams. 40 45

In testimony whereof we have hereunto set our hands in presence of two subscribing witnesses.

JACOBUS HENNEVELD.
ALEXANDER LEMEI.
